UNITED STATES PATENT OFFICE.

OLE C. ABRAHAMSON, OF MINNEAPOLIS, MINNESOTA.

RAILWAY-SPIKE.

No. 861,491.

Specification of Letters Patent.

Patented July 30, 1907.

Application filed March 4, 1907. Serial No. 360,587.

To all whom it may concern:

Be it known that I, OLE C. ABRAHAMSON, a citizen of the United States, residing at Minneapolis, in the county of Hennepin and State of Minnesota, have 5 invented certain new and useful Improvements in Railway-Spikes; and I do hereby declare the following to be a full, clear, and exact description of the invention, such as will enable others skilled in the art to which it appertains to make and use the same.

10 My invention relates to railway spikes and to devices for coöperation therewith to prevent withdrawing of the spikes from the ties, and has for its object to improve the same in the several particulars hereinafter noted.

15 To the above ends the invention consists of the novel devices and combinations of devices hereinafter described and defined in the claims.

20 In the accompanying drawings which illustrate the invention, like characters indicate like parts throughout the several views.

25 Referring to the drawings, Figure 1 is a plan view, showing a portion of the rail and a portion of the tie, secured together in accordance with my invention. Fig. 2 is a vertical section taken on the line $x^2 x^2$ of Fig. 1; and Fig. 3 is a plan view showing one of the so-called tie plates.

30 The numeral 1 indicates a tie, and the numeral 2 a rail of ordinary construction. The numeral 3 indicates a tie plate, so-called, which is placed between the tie and the foot flange of the rail. This tie plate is provided near one end with a spike passage 4, and near its other end with an angular or L-shaped spike passage 5. The spikes 6 are provided with the usual heads, but some little distance below their heads they are 35 provided with outwardly projecting lock shoulders 7, the important function of which will presently appear. Preferably also, the spikes are provided at their extreme lower ends with small projecting pin portions 8 which are adapted to be driven into the tie by a very 40 light blow and to hold the spike in an upright position for driving into the tie. The spike passage 4, in a direction longitudinally of the tie plate 3, and transversely of the rail, is of such length that the spike body and lock lug 7 may be freely passed therethrough. The 45 longitudinally extended portion of the L-shaped spike passage 5 is also of the same length, but the laterally projecting portion 5^a of said passage 5 is only of such width as to pass or receive the body of the spike. The exact relation of the said spike passages with respect 50 to each other and in respect to the spikes and the rail, will be more fully understood by description of the manner of applying the spikes and plate, and of removing the same. The spike at the left with respect to Figs. 1 and 2 must first be driven, and to permit this 55 the tie plate 3 is forced toward the left so that the inner extremity of its spike passage 4 alines approximately

with the outer edge of the left hand foot flange of the rail. Then, when the left hand spike has been driven to position with its lock lug 7 below the plane of the tie plate 3, the said tie plate is driven toward the right 60 as far as it will go, thereby carrying a portion of the left hand end of said tie plate directly over the lock lug 7 of the said left hand spike. This movement of the tie plate brings the inner extremity of the L-shaped spike passage 5 approximately in line with the outer 65 edge of the right hand foot flange of the rail, and the said tie plate should then be positioned approximately as shown by dotted lines in Fig. 3. The right hand spike 6 is then driven to position so as to carry its lock lug 7 below the plane of the tie plate 3. Then, the 70 said tie plate should be moved pivotally on the left hand spike into the position shown by full lines in Figs. 1 and 3, thereby carrying a portion of the right hand end of the tie plate over the lock shoulder of the right hand spike.

75 When the parts are positioned as just stated, it is evident that the spikes are locked into the tie by engagement of their lock shoulders 7 with the tie plate. Otherwise stated, it is impossible then to withdraw either of the spikes from the tie. Any slight tendency 80 that there may be for the spikes to work upward out of the tie will be offset by the downward pressure produced thereon every time a train passes the same, the pressure from the train at such time being transmitted to the spikes, from the rail to the tie plate, and from 85 the tie plate to the lock lugs 7 of the said spikes. Furthermore, the tie plate 3 ties the spikes 6 together in such manner that they can not spread or separate from each other in the tie. Hence, lateral pressures on the rail in either direction will be simultaneously resisted 90 by the spikes on both sides of the rail.

If desired, of course, a small spike or nail may be driven into the tie to positively hold the tie plate 3 in its position shown by full lines in Figs. 1 and 3.

To remove the spikes it will be necessary first to remove the tie plate from the full line position, Figs. 1 and 3, into the dotted line position, Fig. 3, and then to withdraw the right hand spike. Then, to drive the tie plate toward the left as far as it will go and then withdraw the left hand spike.

100 The device described, while extremely simple and of small cost, is highly efficient for the purposes had in view.

What I claim is:

1. The combination with a rail and a tie, of a tie plate 105 interposed between the same and provided with spike passages, of spikes having projecting lock lugs adapted to be passed through perforations in said tie plate to a point below the plane of the tie plate, and which tie plate is adapted to be slid to move portions thereof over the lock lugs of said spikes and thereby hold the said spikes driven into the tie, substantially as described.

2. The combination with a rail and a tie, of a tie plate 110

3 interposed between said rail and tie, said tie plate having near one end a spike passage 4, and having near its other end an approximately L-shaped spike passage 5-5^a, of spikes 6 having outwardly projecting lock lugs 7, adapted to be passed through the perforations of said tie plate, and which tie plate is adapted by endwise and pivotal movement to be so moved that portions thereof will overlie the lock lugs of said spikes and thereby hold the spikes driven in the tie, substantially as described.

10 3. A railway spike having a head at one end and hav-

ing at its other end a small projecting pin portion 8 adapted to be easily driven into a tie to hold the spike in position for driving, substantially as described.

In testimony whereof I affix my signature in presence of two witnesses.

OLE C. ABRAHAMSON.
